UNITED STATES PATENT OFFICE

GEORGE W. DUNHAM, OF NEW YORK, N. Y., ASSIGNOR TO WHIRLDY CORPORATION, OF UTICA, NEW YORK, A CORPORATION OF NEW YORK

PUMPING MECHANISM FOR WASHING MACHINES

Application filed June 18, 1925, Serial No. 37,896. Renewed September 17, 1930.

Special objects of this invention are to provide a pump for washing machines and to combine the pump with the machine in such a way as to preserve the balance of the machine and to be out of the way but at the same time readily accessible.

Other important objects are to arrange for free flow of the washing liquid to the pump, to seal the drive shaft of the pump without resort to stuffing boxes or the like, to provide a simple hose connection for the discharge side of the pump, and in general, to provide an entirely practical and efficient pump structure.

15 Among the novel features of the invention are the location of the pump concentric to the drive shaft of the machine and at the bottom of the tank of the machine, between the gear box and the base of the column which 20 supports the rotating element of the machine; the provision of a well extending from the pump casing up about the drive shaft to form a seal and the connection of the drive shaft with the pump impeller by a 25 sleeve extending down over the outside of said well; the division of the pump casing into upper and lower halves and the gripping of the discharge hose between these halves.

30 These and other novel features of the invention will be considered in detail in the course of the following specification.

The drawings accompanying and forming part of this specification illustrate the invention embodied in one of its practical commercial forms, but it should be understood that the structure may be modified without departure from the broad spirit and scope of the invention as hereinafter defined 40 and claimed.

Figure 1 is a side elevation of the invention as embodied in a washing machine of the type disclosed in my co-pending application, Ser. No. 18,086, filed March 25, 1925.

45 Figure 2 is a broken sectional part plan view of the pump structure as taken on substantially the plane of line 2-2 of Figure 3.

50 Figure 3 is a broken enlarged vertical sectional view of the pump in its relation to the washing machine.

Figure 4 is a detail section illustrating the mounting of the receptacle.

The washing machine in connection with which the invention is illustrated comprises a tank 5 containing a clothes receptacle 6 supported on a hollow column 7 rising from the bottom of the tank and adapted to be rotated by a shaft 8 extending up from the gear box 9 suspended from the bottom of the tank. An electric motor is indicated at 10 driving through a belt 11, the pulley 12 journaled in the gear box and connected by suitable gearing with the drive shaft 8. As this gearing forms no part of the present invention, being fully disclosed and covered in the application referred to, the same is not illustrated in detail. The shaft for driving the agitator 100 is shown at 13 extending up through the receptacle driving shaft which is made hollow for the purpose.

70 The receptacle 6 is provided with a hub 100 journaled on the top of the pedestal 7 by the bearings 101 and 102. The tubular drive shaft 8 and inner drive shaft 31 pass through the hollow pedestal 7, being driven by the 75 gearing in the gear box 9, the solid shaft having imparted thereto an oscillatory rotary motion and the tubular shaft having imparted thereto a continuous rotary motion. An agitator 103 is removably mounted on the 80 top of the inner shaft by a spline connection 104. The receptacle 6 is connected and disconnected from the tubular shaft by a clutch collar 105 feather-keyed to the tubular shaft 8 and having splines 106 engageable with 85 splines 107 on the reduced extension 108 of the hub 100.

For washing the clutch collar 105 is in its lower position and the agitator 103 is mounted on top of the inner shaft as shown in Fig. 90 4. For drying, the agitator 103 is removed from the machine and the clutch collar is in its upper position, to continuously rotate the receptacle to drive water from the laundry.

95 A feature of the invention thus far described is the provision for circulation of water or washing liquid from the bottom of the tank up into the clothes receptacle by way of a supply conduit 14 rising at the side of the tank and terminating in a swing nozzle 100.

zle 15 adapted to discharge into the receptacle into the tank or outside the tank as required. The pump of the present invention supplies the force for this circulation, the same being indicated at 16 in Figure 1, located below the tank, interposed between the foot of the supporting column and the gear box and connected at its discharge side by a conduit 17 with the lower end of the riser 14.

10 The pump casing is shown in Figure 3 as made up of upper and lower halves or sections 18, 19, forming between them a pump chamber in which the impeller 20 operates.

15 The upper casing section is shown as carrying an upstanding hub 21 forming a seat or socket for the supporting column 7 and as having secured to the top of the same by bolts 22, a flange 23 having an upstanding neck or collar 24 surrounded by resilient washers or cushions 25 between which enters the edge of the flange 26 which is secured to the bottom of the tank by the bolts 27. In this fashion the supporting column, pump 20 and gear box are all resiliently connected with and suspended from the tank. The central opening 28 in the tank bottom is of sufficient size to freely pass the hub for the supporting column and the surrounding collar 24, with sufficient space between these two to provide an annular inlet channel 29 opening at the bottom by ports 30 in the top of the pump casing into the axial portion of the pump chamber.

25 30 The pump inlet is shown as screened by a conical strainer 31 fitting closely about the supporting column at the top and seating at its lower end in the annular cavity 32 provided between the supporting neck and the surrounding rim of the tank opening.

35 The two casing sections and the gear box are shown as flanged at their edges and as secured together by bolts 33 passed through said flanges. The bolting together of the 40 parts in this relation is utilized in the illustration as a means for clamping the discharge conduit in place, said conduit section 17 being shown as a piece of hose having a nipple 34 inserted in the end of the same to 45 prevent it from collapsing and this reinforced end is clamped between the cooperating rounded portions 35, 36 of the upper and lower casing sections at the discharge side of the pump. In this way the hose is held to 50 the pump without any exterior clamps or fastenings and the other end of the hose may be simply slipped over an angular extension 37 on the lower end of the riser. This 55 interposed section of flexible hose serves to prevent any vibration being communicated from the pump to the tank, by way of the 60 riser and the elastic washers by which the pump is secured to the bottom of the tank 65 serve as a resilient mounting, cushioning the

parts and preventing vibration being imparted to the tank bottom.

To eliminate the possibility of leakage from the pump down into the gear box, a well 38 is provided extending from the bottom of the pump casing to a point above the highest possible liquid level in the tank. This well is shown as a section of pipe surrounding the drive shaft, seated in a hub 39 extended downward from the bottom half 75 of the pump case and projecting up to a point above the bottom of the clothes receptacle. This tubular water well is shown as standing clear of the drive shaft which it surrounds and the impeller is shown as having a bearing thereon at 40.

70 The impeller is connected with the drive shaft 8, over the upper edge of the water well by a section of tubular shafting 41 on the lower end of which the impeller is fixed 85 and which carries at the upper end, a collar 42 closing the space over the well and secured to the drive shaft by screws 43. By thus interposing a tubular water well about the drive shaft and connecting the pump impeller with the drive shaft over the upper edge of the tubular well, all possibility of leakage is avoided and this without resort to stuffing boxes or tight bearings which consume power and lose efficiency as they wear.

75 The concentric disposition of the pump is of special advantage in enabling a direct drive of the pump without the interposition of any intermediate gearing and this concentric arrangement further has a tendency to balance the mechanism and steady the running of the machine. At the same time this places the pump out of the way but leaves it readily accessible.

80 While I have shown and described and have pointed out in the annexed claims certain novel features of my invention, it will be understood that various omissions, substitutions and changes in the forms and details of the device illustrated and in its operation may be made by those skilled in the art without departing from the spirit of my invention.

85 What is claimed is:

1. In apparatus of the character disclosed, a horizontally disposed rotary pump, a drive shaft extending freely up through the rotary element of the pump, a tubular water well extending from the bottom of the pump casing up around said shaft and a tubular shaft connected with the rotary element of the pump, extending upwardly around the water well and connected with the drive shaft over the top of the water well, the top of the pump casing having upstanding hubs 100 spaced to provide an annular channel forming an inlet to the pump.

105 2. In apparatus of the character disclosed, a horizontally disposed pump having a rotary element and a casing separable on a hori-

zontal line, a gear box, said gear box and the pump case sections having horizontally extending flanges, fastenings securing said flanges together, vertical shafting extending from the gear box up through the rotary element of the pump and drive connections from said shafting to said rotary element, including a tubular shaft connected with the rotary element of the pump and with the drive shaft 10 at a point above the pump and a stationary tubular bearing for the rotary element extended upward inside the tubular pump shaft.

3. In combination, a rotary pump casing 15 having upper and lower flanged sections, a gear box below said pump casing having a flange matching the flanges of the casing, fastenings securing said gear box and casing flanges, shafting extending from the gear box 20 up through the pump casing, an impeller within the pump casing concentrically disposed about said shafting and a tubular drive member connected to said shafting at a point above the pump casing and to said impeller.

25 4. In combination, a rotary pump casing having upper and lower flanged sections, a gear box below said pump casing having a flange matching the flanges of the casing, fastenings securing said gear box and casing 30 flanges, shafting extending from the gear box up through the pump casing, an impeller within the pump casing concentrically disposed about said shafting, a tubular drive member connected to said shafting at a point 35 above the pump casing and to said impeller and a tubular well extending from the lower section of the pump casing up about the drive shafting inside the tubular drive connection.

5. In combination, a rotary pump casing 40 separable at right angles to the axis of the pump and provided with cooperating portions forming the discharge outlet of the pump, a flexible hose entered in said outlet passage between the casing sections and a 45 tubular liner in such inserted portion of the hose, preventing collapsing of the same under the clamping action of said sections.

6. In apparatus of the character disclosed, a tank having a bottom opening, a rotary 50 pump beneath the tank and in communication therewith through said bottom opening, said pump having a laterally extending discharge conduit and a riser extending from said discharge conduit into communication 55 with the interior of the tank, said riser being rigidly secured to the side of the tank and the discharge conduit of the pump having a section of flexible hose interposed therein and means for resiliently supporting the 60 pump from the bottom of the tank.

7. In apparatus of the character disclosed, a tank, a pump in communication with said tank, means for resiliently supporting said pump from the bottom of the tank, a conduit 65 rigidly attached to the tank and a flexible

conduit section connected between the pump and said rigidly attached conduit.

8. In a machine of the character disclosed, a tank having an opening in the bottom of the same, a rotary pump having a supporting hub extending up through said bottom opening, the pump having an inlet passage in the top of the same within said hub and a lateral discharge passage beneath the tank and means for supporting said pump by said hub.

9. In apparatus of the character disclosed, a horizontally disposed pump casing, a hub extended upward from said pump casing providing a seat for a supporting column, a second hub extended upward from the top of the pump casing and spaced from the first hub to provide an annular inlet channel, the top of the casing having ports therein opening to said channel and means for supporting the pump engaged with said outer hub.

In testimony whereof I have hereunto set my hand.

GEORGE W. DUNHAM.
